UNITED STATES PATENT OFFICE

CLIFFORD A. BARDEN, OF OBERLIN, OHIO

DESIGN FOR A GOLF SCORE CARD

Application filed May 2, 1931. Serial No. 39,889. Term of patent 3½ years.

To all whom it may concern:

Be it known that, CLIFFORD A. BARDEN, a citizen of the United States of America, residing at Oberlin, in the county of Lorain and State of Ohio, has invented a new, original, and ornamental Design for Golf Score Card, reference being had to the accompanying drawing, forming part thereof.

The figure is a plan view of a golf score card showing my new design.

The design is of no appreciable third dimension, being wrought upon a piece of thin cardboard.

I claim:

The ornamental design for a golf score card, as shown and described.

In testimony whereof I affix my signature.

CLIFFORD A. BARDEN.
